UNITED STATES PATENT OFFICE.

CHARLES R. CAMPBELL, OF ERIE, PENNSYLVANIA.

LIP-PRESSURE-CORRECTING DEVICE FOR WIND INSTRUMENTS.

Application filed December 2, 1921. Serial No. 519,355.

To all whom it may concern:

Be it known that I, CHARLES R. CAMPBELL, a citizen of the United States, residing at Erie, in the county of Erie and State 5 of Pennsylvania, have invented new and useful Improvements in a Lip-Pressure-Correcting Device for Wind Instruments, of which the following is a specification.

This invention is designed to assist musicians in correcting the lip pressure used 10 with wind instruments. As is well understood if an artist uses excessive lip pressure for an extended time it results in serious injury to the artist. The correction is accomplished in two ways, first, by indicating the 15 pressure on the mouth-piece in a manner that it may be observed by the operator and also by providing the instrument with means which will make it inoperative upon 20 a pre-determined lip pressure.

The invention is illustrated in the accompanying drawings as follows:-

Fig. 1 shows an elevation of the dial as 25 operated by the device.

Fig. 2 a central longitudinal section through the device.

Fig. 3 a cross section on the line 3-3 in Fig. 2.

Fig. 4 a plan view of the mounting.

Fig. 5 a view of the dial of an alternative construction.

Fig. 6 a central longitudinal section of the same.

Fig. 7 a central longitudinal section of a 35 variation.

1 marks the mouth-piece, 2 the horn or instrument conduit, and 3 the body of a mounting which is inserted between the mouth-piece and the conduit, the body 3 being provided with a plug 4 rigidly secured 40 to it having the inwardly projecting tapered end 5 adapted to be inserted into the wind conduit in the manner of the mouth-piece. A plunger 6 is slidably mounted in the body 3 and fits telescopically over a projection 5^a on the end of the plug 4 making a fit sufficiently close to confine the air but permitting a movement of the plunger. A spring 7 is arranged between the plunger 50 and the plug 4, the spring resisting the movement of the plunger. A dial case 10 is carried by a tube 8 extending into an opening 9 in the body 3. The case 10 is provided with a dial 12 and a hand 13. The hand 13 is mounted on a drum or spool 14 and the drum or spool is mounted on a pin

15 fixed in the case 10. A spring 16 is wound around the spool and secured to the case and tends to return the hand to zero. A cord 17 is wound on the drum carried 60 over a pulley 18 extended through the pipe 8 carried over a pulley 19 and secured to a screw 20 mounted on the plunger 6.

It will readily be seen that as the plunger 6 is moved forward under pressure from the mouth-piece and against the resistance of the spring 7 that the cord 17 will be drawn with it effecting a turning movement of the drum 14 and with the drum the hand 13. The spring is so proportioned with relation 70 to the dial that the dial will indicate the lip pressure which will move the plunger against the spring a sufficient distance to move the hand as indicated in the dial.

The plunger is provided with an opening 75 21 which is covered by a valve 22. This valve is slidably mounted in a slot 23 in the bottom of the body 3 and held in position by a clip 23^a which extends up around the body a sufficient distance to hold the valve yieldingly in place. When the plunger reaches a pre-determined position forward where it is desired to make the instrument inoperative the opening 21 passes over the end of the valve 22 and thus permits an 80 escape of air which renders the instrument inoperative for proper tone production. By making the valve 22 adjustable along the slot 23 the point at which the instrument is 85 made inoperative may be adjusted to any lip pressure desired.

In the alternative construction shown in Figs. 5 and 6 a body 24 is provided in which there is a plug 25. A plunger 26 moves between the body 24 and the plug 25 trapping 90 liquid in a space 27. The space 27 communicates by means of a passage 28 with a pressure gauge 29. It will readily be seen that as the plunger is moved forward liquid is forced from the space 27, passage 28 to the 95 pressure gauge and this will indicate the pressure to which the plunger is subjected through lip pressure on the mouth-piece.

In the alternative construction shown in Fig. 7 the body 30 is provided with a plug 100 31. A plunger 32 is slidably mounted in the body 30 and telescopes the plug 31.

A spring 33 resists the movement of the plunger. A bell crank lever 35 has one arm extending into an opening in the plunger 110 and the opposite arm 36 engaging a plunger 37. The plunger is graduated at 38 extend-

ing through a sleeve 39, the graduations indicating the lip pressure to which the mouth-piece is subjected.

What I claim as new is:—

- 5 1. In a lip pressure correcting device for wind instruments, the combination of a spring resisted mouth-piece; and means offset from the mouth-piece actuated by lip pressure on the mouth-piece for indicating 10 to the player of the instrument said lip pressure.
- 15 2. In a lip pressure correcting device for wind instruments, the combination of a spring resisted mouth-piece; and means for indicating the lip pressure on the mouth-piece comprising a dial and indicating hand.
- 20 3. In a lip pressure correcting device for wind instruments, the combination of a spring resisted mouth-piece; a wind conduit; a movable connection between the mouth-piece and the conduit; means resisting the movement of said connection; and devices actuated by the movement of said connection for indicating the lip pressure 25 on the mouth-piece comprising a dial and an indicating hand; a drum on which the hand is mounted; and a cord on the drum, said cord being actuated by a movement of the connection.
- 30 4. In a lip pressure correcting device for wind instruments, the combination of a mouth-piece; a plunger in which the mouth-

piece is mounted; a body in which the plunger is mounted; a connection on the body for the wind conduit; a spring resisting the movement of the plunger; and an indicator comprising a dial, a hand operating on the dial, a drum carrying the hand, and a flexible connection from the drum to the plunger actuating the hand with a movement of the plunger.

5. In a lip pressure correcting device for wind instruments, the combination of a spring resisted mouth-piece; means off-set from the mouth-piece for indicating to the 45 player of the instrument the pressure on the mouth-piece; and means rendering the instrument inoperative upon a pre-determined pressure on the mouth-piece.

6. In a lip pressure correcting device for 50 wind instruments, the combination of a spring resisted mouth-piece; a plunger in which the mouth-piece is mounted, said plunger having an opening therethrough; a mounting for the plunger having a slot 55 registering with the opening; a valve plate in the slot; means for holding the valve plate adjustably in the slot; and a pressure indicating device actuated by the movement of the plunger.

In testimony whereof I have hereunto set my hand.

CHARLES R. CAMPBELL.
